DESIGN FOR A LADY'S HAND BAG

Nathan Sloane, New York, N. Y.

Application September 23, 1933. Serial No. 49,328

Term of patent 3½ years

To all whom it may concern:

Be it known that I, NATHAN SLOANE, a citizen of the United States, residing at New York city, in the county of New York and State of New York, have invented a new, original, and ornamental Design for a Lady's Hand Bag, of which the following is a specification, reference being had to the accompanying drawing, forming a part thereof.

Fig. 1 is a front elevational view of a lady's hand bag showing my new design.

Fig. 2 is a side view of the same.

Fig. 3 is a rear view of the hand bag shown in Fig. 1 with the chain member omitted.

I claim:

The ornamental design for a lady's hand bag as shown.

In testimony whereof I have affixed my signature.

NATHAN SLOANE.
